SAFETY MINE CAR SCOTCH

George Walter Stone, Yukon, W. Va.

Application February 2, 1935, Serial No. 4,701

3 Claims. (Cl. 104—257)

The present invention relates to a safety mine car scotch designed to secure standing cars on the track and so prevent accidents from runaway cars.

5 The advantage of this scotch is its extreme ease of operation and its adaptability to any condition or any type of car, it can be used either in front, behind, or between the wheels of the car and so prevent runaways in any direction. 10 It can be used not only at the face but anywhere where the cars are left standing.

Another important feature of the invention resides in the provision of a safety scotch of this nature which is simple in its construction, easy 15 to install and remove, inexpensive to manufacture, reliable and efficient in use and otherwise well adapted to the purpose for which it is designed.

With the above and numerous other objects in 20 view as will appear as the description proceeds, the invention consists in certain novel features of construction, and in the combination and arrangement of parts as will be hereinafter more fully described and claimed.

25 In the drawings:

Figure 1 is a side elevation of a scotch embodying the features of my invention showing the same installed on a rail.

Figure 2 is a sectional view taken substantially on the line 2—2 of Figure 1 looking in the direction of the arrows.

Figure 3 is a similar view showing the scotch block swung out of the way.

Figure 4 is a detail top plan view of the scotch block.

Figure 5 is a detail top plan view of the mounting block.

Figure 6 is a side elevation thereof.

Figure 7 is a sectional view therethrough taken 40 substantially on the line 7—7 of Figure 6.

Figure 8 is a top plan view of the clamping plate.

Figure 9 is a fragmentary side elevation of a low type mine car showing an adaptation there- 45 with of a modified form of the scotch block, and illustrating the extension shoe about to be applied.

Figure 10 is a view similar to Figure 9 with parts of the scotch block broken away, and showing the extension shoe in applied position.

Figure 11 is a fragmentary top plan view of the modified form of the scotch block with the extension shoe removed.

Referring to the drawings in detail, it will be 55 seen that numeral 5 denotes a supporting block

having an inner face 6 to abut web 7 of the rail, an inclined upper face 8 to abut the underface of one side side of the ball 9 of the rail and an inclined lower face 9' to abut one side of the upper face of the base 10 of the rail and provided on the outer face adjacent the upper edge thereof with a plurality of apertured ears 11 in spaced relation. A clamp plate 12 extends under the base 10 and on one end has an overhanging flange 14 and at the other end has stud bolts 15 10 for receiving apertured ears 16 depending from the block 5 to be impinged against by nuts 17 on the stud bolts. The scotch block 19 has arms 20 extending between the ears 11 and apertured to receive pin 21 also extending through the 15 apertured ears 11 so as to swingably mount the arm so that the block 19 may be placed on the rail as shown in Figures 1 and 2 or swung out of the way as shown in Figure 3. In order to brace the block when on the rail, there is an overhang- 20 flange 22 provided on the scotch block. Of course, the scotch block is provided at each end with the curved beveled portions 25 to receive the wheel as indicated to advantage in Figure 1 in dotted lines.

It very often happens in mines that the body B of the cars are necessarily of low construction, leaving very little space between the ball of the track rail and the bottom of the body. In this construction of the cars the height of the 30 scotch block 19 would necessarily be reduced to allow the block to be swung up into position on the ball of the rail and with the height of the scotch block 19 being reduced there is the possibility of the block not offering enough of a but- 35 tress to hold the car in chocked position. To meet such an exigency I have illustrated the modified form of the scotch block in Figures 9, 10 and 11.

When cars with low hung bodies B are con- 40 structed, the wheels 30 thereof are mounted in forward and rearward cavities, one of which is indicated at 31, and to accommodate maximum capacity in the body B very little space as indicated at 32 can be allowed between the tread of 45 the wheels and this cavity. Now, to accommodate a sufficient buttress to hold the cars securely chocked, I provide a cavity 33 in each end of the scotch blocks 19, extending inwardly from the upper portions of each curved, beveled face 25. 50 In each cavity is rockably mounted an extension shoe 34 rockably mounted intermediate its end on a pin 35 and the ends of the pin are seated in openings 36 in the side walls of the scotch block 19.

One end of the extension shoe 34 is longer and slightly heavier than the other which permits the longer end to project outwardly of the cavity 33 under normal conditions. The other shorter end in this event is held within the cavity 33 as illustrated in Figure 9 and the free end in Figure 10. In the normal position, the longer end of extension shoe 34 clears the bottom of the body B of the car. When the scotch block 19 is thrown upwardly resting on the ball of the track rail and the car moving from right to left in Figure 9 of the drawings, the longer end of the extension shoe 34 on the right end of the scotch block bears against the tread of the wheel and as the car moves further from right to left the extension shoe will present the entire face thereof as a buttress to the wheel 30 as shown in Figure 10 of the drawings. As shown in Figure 10 of the drawings it will be seen that the extension shoe provides greater chocking surface than could be obtained by merely using the arcuate beveled face 25 against the flange of the wheel, while at the same time the longer end of the extension is made to fit snugly in the space 32 between the cavity 31 and the wheel 30.

In all other respects, the scotch block 19 is the same as described in connection with Figures 1 to 8 inclusive.

When the device shown in Figures 9 to 11, inclusive, is to be used, the member 19 is first swung to inoperative position, as indicated in Figure 3, and then the car is advanced until the space between a pair of wheels is located opposite the member. Then the member 19 is swung upwardly on the rail between the pair of wheels, so that one of the members 34 will engage the rear wheel, as shown in Figures 9 and 10.

It is thought that the construction, utility and advantages of this invention will now be quite apparent to those skilled in this art without a more detailed description thereof.

The present embodiment of the invention has been described in considerable detail merely for the purposes of exemplification since in actual practice, it attains the features of advantage enumerated as desirable in the statement of the invention and the above description.

It will be apparent that changes in details of construction, and in the combination and arrangement of parts may be resorted to without departing from the spirit or scope of the invention as hereinafter claimed or sacrificing any of its advantages.

Having thus described the invention, what is claimed as new is:

1. A device of the class described including, in combination, a block, means for clamping the block to a track rail, a second block, means for swingably mounting the second block on the first block so that the second block may rest on the rail for the purpose of providing a chock, said second block formed with a cavity, an extension shoe rockably connected to the second block and having one end normally projecting from the second block and the other end normally seated in the cavity whereby the projecting end is moved by the wheel of a car to be chocked to present the entire length of the shoe as an additional buttress.

2. A device of the class described comprising, in combination, a block, means for swingably mounting the block on a track rail, said means permitting the block to be swung so as to be mounted on the rail or to one side of the rail and when mounted on the rail providing a chock, said block being formed with a cavity, an extension shoe rockably mounted on the block and having one end normally projecting from the block and the other end normally seated in the cavity whereby the projecting end is moved by the wheel of a car to be chocked to present the entire length of the shoe as an additional buttress.

3. A device of the class described comprising a block, means for holding the block with its lower edge resting on the head of a rail, said block having a cavity in a wheel engaging edge thereof, an extension shoe mounted for rocking movement in the cavity and having one end normally projecting from the block and the other end normally seated in the cavity, whereby the projecting end is moved by the wheel of a car to be chocked, to present the entire length of the shoe to the wheel.

GEORGE WALTER STONE.
